UNITED STATES PATENT OFFICE.

FREDERIC KETTLER, OF MILWAUKEE, WISCONSIN.

IMPROVED HEEL FOR BOOTS OR SHOES.

Specification forming part of Letters Patent No. 35,377, dated May 27, 1862.

To all whom it may concern:

Be it known that I, FREDERIC KETTLER, of Milwaukee, State of Wisconsin, have invented a new and Improved Metallic Heel for Boots or Shoes; and I do hereby declare that the following is a full and exact description thereof, reference being had to the accompanying drawings, and to the letters of reference marked thereon.

The nature of my invention consists in an improvement on metallic heels for boots or shoes.

The purpose of this invention is to construct a cheap, neat, and durable heel.

Figure 1 gives a profile view of this heel. Fig. 2 is a sectional view of the same. Fig. 3 shows the rows of nails at the bottom. Fig. 4 is a side view of those nails.

Fig. 1 represents the iron casing of this heel with the teeth A, by means of which the heel is fastened to the boots or shoes.

Fig. 2 shows the angle B. This consists of a piece of sheet-iron, which is bent in the shape of an angle and which runs parallel with the outer casing. The upper end of said angle is fastened to the casing by means of rivets, and the lower end or bottom piece of this angle forms the two or three rows of nails, which are

constructed by cuts made in the plate. The purpose of these nails is to make the heel more durable. Space C is to be filled with gutta-percha or leather. Space D may be filled with any substance.

Fig. 3 represents a modification of Fig. 1, the iron casing, instead of being continuous, having sections cut out to reduce the weight of the metal, and having the remaining portion of the casing, excepting that reserved for the teeth, filled up and covered with gutta-percha.

Fig. 4 gives a profile view of Fig. 3.

What I claim as my invention, and desire to secure by Letters Patent, is—

1. A heel composed of an iron casing constructed with the teeth, as described, in combination with a filling in whole or only in the tread, of gutta-percha.

2. The combination of the casing, constructed, as described, with a covering, up to the line of the teeth, of gutta-percha, and a filling of the same or other material, in the manner described.

FREDERIC KETTLER.
